CLAIM

The ornamental design for a “bite regulator,” as shown and described.

DESCRIPTION

FIG. 1 is a top, front, and right side perspective view of one example of my new design for a bite regulator.

FIG. 2 is a front view of the bite regulator shown in FIG. 1. FIG. 3 is a rear view of the bite regulator shown in FIG. 1. FIG. 4 is a top view of the bite regulator shown in FIG. 1. FIG. 5 is a bottom view of the bite regulator shown in FIG. 1.

FIG. 6 is a left side view of the bite regulator shown in FIG. 1, the right side view being a mirror image thereof.

FIG. 7 is a top, front, and left side perspective view of another embodiment of my new design for a bite regulator. FIG. 8 is a front view of the bite regulator shown in FIG. 7. FIG. 9 is a rear view of the bite regulator shown in FIG. 7. FIG. 10 is a top view of the bite regulator shown in FIG. 7. FIG. 11 is a bottom view of the bite regulator shown in FIG. 7; and,

FIG. 12 is a right side view of the bite regulator shown in FIG. 7, the left side view being a mirror image thereof.

The broken lines showing in the figures represent portions of the bite regulator that form no part of the claimed design.
